DESIGN FOR A LOCOMOTIVE HEADLIGHT

Jeremiah D. Kennelly, Oak Park, Ill.

Application November 1, 1937, Serial No. 72,546

Term of patent 14 years

To all whom it may concern:

Be it known that I, Jeremiah D. Kennelly, a citizen of the United States, residing at Oak Park, in the county of Cook and State of Illinois, have invented a new, original, and ornamental Design for Locomotive Headlights, of which the following is a specification, reference being had to the accompanying drawing, forming a part thereof.

Figure 1 is a side elevation of a locomotive headlight, showing my new design.

Figure 2 is a front elevation of the same headlight.

I claim:

The ornamental design for a locomotive headlight, as shown.

JEREMIAH D. KENNELLY,
